UNITED STATES PATENT OFFICE.

ABNER D. THOMAS, OF LITTLE ROCK, ARKANSAS, ASSIGNOR TO THOMAS GIN-COMPRESS COMPANY, A CORPORATION OF ARKANSAS.

COTTON-PRESS.

SPECIFICATION forming part of Letters Patent No. 699,935, dated May 13, 1902.

Application filed September 16, 1901. Serial No. 75,573. (No model.)

To all whom it may concern:

Be it known that I, ABNER D. THOMAS, a citizen of the United States, residing at Little Rock, in the county of Pulaski and State of 5 Arkansas, have invented certain new and useful Improvements in Cotton-Presses, of which the following is a specification, reference being had to the accompanying drawings, forming a part thereof.

10 The invention to be hereinafter described relates to cotton-presses, and more particularly to that type of such presses wherein the cotton is assembled in layers in a baling box or chamber under any desired degree of compression and thereafter transferred to the finishing side of the press for any desired pressure or it may be for final compression into a compact bale for shipment.

It is the usual practice at the present time 20 to bale the cotton at the gin-house in large but loosely-packed bales, which are transferred to distant points and compressed to the size and density desired by heavy and powerful compresses; but this method of 25 baling necessitates repeated handling of the cotton, first, in the production of the loose bale at the gin, and, second, in the shipment to the central or distant point for compression. To obviate these obvious ob-

30 jections, attempts have been made to provide a baling-press that could assemble the cotton in layers under more or less compression as it came from the gin and upon the completion of the bale to transfer it with as little 35 handling as possible to the finishing side of the press, where the bale was subjected to the final compression desired. In such form of presses, however, where the layers of cotton are subjected to more or less pressure as 40 they are formed into the bale, it is obvious that as the bulk or weight of the bale increases the pressure of the bale-forming means upon the top of the bale decreases and at a ratio proportionate to the increasing 45 weight of the bale. It is likewise obvious in such form of presses that upon completion of the preliminary bale on the bale-forming portion of the press unless some means are provided to compress or hold the top layers 50 of the cotton below the bale-forming means or head of the press it will be impossible to

successfully move the bale from its forming position to the finishing side of the press, as the elasticity of the compressed layers of cotton will at once cause the bale to spring 55 upward as soon as the pressure is removed, and by virtue of the increase in size the bale cannot thereafter be placed beneath the head of the press on the finishing side. In laying the layers of cotton during the formation of 60 the preliminary bale the fold of the lap as each layer is put in is liable to kink on the inner side of the fold, and if the lap is made thick and great pressure exerted on the lap at that point the fiber of cotton becomes in- 65 jured.

With the above general defects and objections in view it is the object of my present invention to provide a press for the production of square or rectangular bales of cotton 70 as the latter is delivered from the gin, and in which upon the completion of the preliminary bale it may be at once subjected to the necessary compression on the finishing side of the press to expel the air and form the fin- 75 ished bale of great density.

Generally stated, my invention consists of the devices and combination of parts, as will hereinafter be more fully described, and definitely pointed out in the claims. 80

In the drawings, Figure 1 is a side elevation of one form of press embodying my invention, some of the parts being shown in section. Fig. 2 is a like view of the press looking in the direction of the arrow, Fig. 1. 85 Fig. 3 is a perspective view on an enlarged scale, showing more particularly the bale-forming side of the press, the hopper, its connected parts, and the cut-off being placed in position above the bale. Fig. 4 is a detached 90 detail view showing the cut-off and one form of means for forcing it down upon the layers of cotton composing the bale. Fig. 5 is a detached side view of a modified form of device for forcing the cut-off upon the top of the 95 bale, and Fig. 6 is a plan view of the parts shown in Fig. 5.

In the present embodiment of my invention I have selected for illustration the type of cotton-press described in my former patent, 100 No. 549,861, wherein two baling boxes or chambers are mounted upon a circular plat-

form or turn-table, so that as the preliminary bale is being formed in one of said boxes or chambers the cotton in the other may be compressed to the required density of the finished 5 bale.

Referring to Fig. 1, A A' represent any suitably-shaped baling boxes or chambers mounted upon the turn-table B, the latter being mounted to turn upon a central vertical shaft 10 B', supported in any desired framework, all as set forth more fully in my former Letters Patent referred to, and which need not, therefore, be herein further described. Located beneath the turn-table B and in position to 15 be directly beneath the baling boxes or chambers A A' when the parts are in position, as indicated in Fig. 1, are two pressing devices A² A³, preferably of the hydraulic type, although, as will be apparent, any desired form 20 or character of such devices may be employed, the purpose thereof being to furnish power to hold the layers of cotton under any desired amount of compression while the preliminary bale is being formed in the chamber or 25 box A' and simultaneously with the formation of the preliminary bale in the chamber or box A' to subject the bale in box A to the finishing compression. Mounted above the turn-table B at one side thereof and in a position 30 to be reciprocated over one of the baling boxes or chambers A A' to form the preliminary bale is a traveling carriage C, comprising any desirable or suitable framing adapted to support the hopper C', which is 35 open at its top and preferably receives the ginned cotton in a fluffy form direct from the condenser D through any usual or desired form of feeding-chute D'. Secured in a suitably rigid manner in proximity to the carriage C and preferably on either side thereof are the tracks or supporting-beams C², by or 40 through which the traveling carriage C is supported and guided during its reciprocations over the baling box or chamber by 45 means of the rollers c c, mounted on the framing c' c' of the carriage above and below said tracks or beams. Secured to the reciprocating carriage C to give reciprocating movement thereto are the rack-bars C³, 50 which may be given reciprocating movement through any suitable source of gearing, as by the pinions C⁴, driven alternately first in one direction and then in another from suitable driving power, the reciprocations of the 55 carriage being such that it travels back and forth over the top of the baling box or chamber and for a distance substantially equal to the width of the box or chamber. Within the hopper C' are mounted the rolls c² c², over 60 which pass the endless feed-belts c³, which serve to feed the cotton as it is delivered into the hopper down between the rolls c² c². Mounted in the carriage C and below the rolls c² c² are the drawing and compressing rolls 65 c³ c³, which by means of any suitable gears or pinions c⁴ and c⁵ are driven one from the other, and the pinions c⁵ being of less diameter

or having less teeth than the pinions c⁴ the drawing and compressing rolls c³ c³ are driven at a faster speed than are the rolls c² c², the consequence of which is that as the material being delivered from the gin or condenser into the hopper is formed into a lap between the rolls c² c² the drawing and compressing rolls mounted below them serve to draw out 70 the lap, and thereby arrange the fibers of the lap in a more nearly parallel condition, so that as the lap is folded layer upon layer in the baling box or chamber the fibers of cotton on the inside of the fold are simply bent back upon themselves without being kinked and without liability to injury upon great compression being brought to bear upon the finished bale. In the illustration of this part 75 of my invention I have shown simply one pair of drawing and compressing rolls c³; but of course it is evident that the number of these rolls may be increased as desired, and where a very thin bat is desired to be formed into a bale such drawing and compressing 80 rolls may be multiplied in number to secure the desired quality and body in the resulting lap as it passes to the baling box or chamber. Mounted upon the lower portion of the traveling carriage are a series of rolls c⁶, around 85 which pass endless belts E E', the said belts being held stationary by a suitable connection e to a fixed part of the adjacent framework, as shown in Fig. 2. Each of the belts E E' referred to carries at a portion of its surface starting-fingers e', which serve as the carriage is reciprocated across the top of the bale to engage the lap upon each change or reciprocation of the carriage, so as to start 90 the lap to fold backward upon itself and be 95 readily fed in another layer upon the bale. It will be noticed in this connection that the fingers e' e' are in such position on the belts E E' that when the carriage is at one end of 100 its travel, as in Fig. 2, the starting-finger e' on the belt E' is in position to engage the lap and fold the same, as above specified, while the starting-finger e' on the belt E is in opposite relation on its belt and will assume position between the two belts similar to that 105 as shown in Fig. 2 when the carriage has reached the other end of its travel.

From the construction so far described it will be seen that as the carriage C is reciprocated back and forth over the top of the bale 110 the usual follower E² (shown, for instance, in dotted lines in Fig. 1) has laid upon it the layers of the bat which has been fed from the traveling hopper, the said follower being held up to exert suitable pressure upon the layers 115 or folds of cotton between it and the belts E E' by means of the pressure device A³, located directly beneath the bale box or chamber, the said pressure in the present embodiment of my invention comprising a hydraulic cylinder 120 in which works the usual piston (not shown) carrying the rod E³, which is adapted to pass into the bale box or chamber beneath the follower E². It will be evident that in 125 130

the formation of a bale and as the cotton is laid upon the follower E² that the pressure between the follower and the aprons E E will decrease in a ratio depending upon the weight 5 of the layers of cotton laid upon the follower, so that without devices being provided to meet this condition the pressure upon the upper layers of cotton in the bale would be less than the pressure upon the remaining portion of 10 the bale, or, in other words, the bale would not be homogeneous nor of uniform density, for which reason I have provided devices for causing a differential resistance or pressure to be exerted upon the bale as its weight or 15 bulk increases. The form of such device as I have selected to illustrate as embodying this feature comprises a cone-pulley E⁴, as shown in Fig. 2, mounted upon the shaft E⁵, which is carried in bearings E⁶ in proximity 20 to the rod or plunger E³, upon which I have provided a series of rack-teeth E⁷, which are adapted to be engaged by a suitable gear or pinion E⁸, mounted upon the shaft E⁵. A weight W, suspended by a flexible connection 25 W' from the cone-pulley E⁴, is adapted to exert a balancing or upward pressure upon the piston or rod E³, depending upon the radius of the cone-pulley E⁴ at the particular point of suspension of the weight. Thus 30 when the follower E² is having the first layers of cotton laid thereon and the plunger or rod E³ is extended into the bale box or chamber to support the follower and compress the 35 layers of cotton it will be evident that the weight of cotton upon the follower will be small, and consequently that the balancing effect for the weight of cotton will likewise be small, so that I have disposed parts of the differentiating pressure device so that at this 40 time the weight W will be suspended from the cone-pulley E⁴, near the smaller diameter thereof, as shown in Fig. 2; but as the weight of cotton increases and the plunger or rod E³ is depressed into the cylinder A³ the cone-pulley E⁴ by virtue of the rack and pinion E⁷ and E⁸ will be turned to wind up the flexible 45 connection E⁹, the weight progressively suspended from said pulley toward its larger diameter, thereby increasing the counterbalancing effect of the weight. While I have 50 described this form of counterbalancing device for the bale, it is evident, of course, that it may be varied in form, and it is not my desire to be limited to the particular 55 form of counterbalancing device described. The preliminary bale having been formed, as above indicated, by the layers of cotton being laid and folded back and forth by the traveling carriage it is evident that on the 60 completion of the preliminary bale the bale box or chamber will be practically full of compressed layers of cotton, the tendency of which will be to expand more or less and to bear with pressure, depending upon the 65 amount of compression given the preliminary bale by the pressure device against the belts E E', and as it is desirable upon the comple-

tion of the preliminary bale to turn the table and place such preliminary bale beneath the finishing compression-head P to give the bale 70 its finishing pressure it becomes necessary to provide some means for holding the cotton in the bale box or chamber while it is being transferred from under the traveling carriage to a position under the finishing compression-head P, and such device I will now proceed to describe.

Referring to Fig. 3 of the drawings, d d designate two handle-bars, pivoted at d' to the frame of the traveling carriage, and preferably, it may be, upon the journal or axis of one of the rolls c⁶. Extending between the handle-bars d d are the pieces d² d², from which depend push-bars d³, the lower ends of which are bifurcated, as at d⁴, and, as more 80 clearly shown in Fig. 4, to engage the bars f of the cut-off frame F, the latter preferably comprising a series of parallel bars f, joined at one end by the cross-bar f' and having upturned ends f², for a purpose that will hereinafter appear. The cut-off frame F is placed 85 upon the bale below the journals of rolls c⁶ and is then pressed upon the top of the bale by the handle-bars and push-bars to carry the top layer of cotton sufficiently away from 90 the belt E' to permit movement of the bale from under the belt, the said cut-off being retained in such depressed condition by means of hooks, as g, which may, if desired, be eccentrically mounted on the cross-bars g' of 95 the bale box or chamber, as shown, so that after the hooks have engaged the bars f of the cut-off they can be forcibly lowered by 100 turning the eccentric g² by means of the handle g³, though such form of construction is 105 not essential. In order that the cut-off frame may be inserted between the rollers c⁶ and the top of the bale, the said rollers c⁶ on one side of the traveling carriage are grooved, as 110 at g⁴, and instead of having a single belt extending the full width of the rollers c⁶ a plurality of smaller belts g⁵ are employed, each of a width corresponding to the distance between the rollers c⁶, as clearly indicated by 115 Fig. 3. From this construction it will be apparent that the cut-off frame can be readily inserted above the bale after the same has been completed by pushing the free ends f² in the grooves of the rollers c⁶ below the axes thereof, the turned-up ends f² during such 120 movement of the cut-off F preventing the bars from becoming embedded in the cotton. When the cut-off F has thus been inserted over the top of the bale, the push-bars d³ are lowered between the sections g⁵ of the belt to 125 bear upon the top of the cut-off, as shown in Fig. 4, force being then applied to the handle-bars d to depress the cut-off that it may be engaged with the hooks g, and when so engaged the cut-off F holds the cotton on top 130 of the bale from pressing contact against the sections of the belt E'.

From the above description and the showing made by the drawings it will be obvious

that the purpose of the cut-off F is to hold the cotton in the bale box or chamber, so that the layers of cotton will not project upward under their elastic force, but will be held by 5 the cut-off in their proper relation in the bale box or chamber, so that the said bale box or chamber with its contained preliminary bale of cotton may be removed from under the bale-forming surfaces, such as the belts 10 E E', and transferred by rotation of the turn-table to the opposite side of the press for the finishing compression or, it may be, for partial compressions, after which it may be tied and taken from the machine for future compression after the cotton in the preliminary bale has become cured and dried, which might 15 be the case where cotton either in the green state or wet had been put up in the preliminary bale, and while I have shown the form 20 of cut-off as consisting of a frame F, as shown in Fig. 4, it is evident, of course, that the construction thereof may be varied between wide limits, its essentials being that it shall be susceptible of insertion above the top of 25 the bale and then clamped to the bale-box, while the bale itself remains under the compression exerted by the pressure devices and the bale-forming surface, as E'.

The form of devices for forcing the cut-off 30 down upon the top of the bale after its insertion above the bale, as specified, are shown in their preferred constructions in Figs. 3 and 4; but it will be evident that such form of cut-off depressor is not essential and that any 35 means may be employed which will operate between the sections of the bale forming surface or belt E' to force the cut-off upon the top of the bale, and as an illustration of such different forms of cut-off depressors I have 40 shown the modification thereof in Figs. 5 and 6, wherein the rolls c⁶¹ comprise several small pulleys mounted on the same shaft, as c⁶², and around each series of row of such pulleys c⁶¹ a section g⁵ of the bale-forming surface E' passes. Mounted upon the axis of 45 one of the rolls c⁶¹ are a series of cams k, fixed to said axis and operable from one side of the machine by means of a handle k', fixed to the extended end k² of the shaft c⁶². It will be 50 obvious upon reference to Figs. 5 and 6 that the cut-off frame F, having been inserted above the bale between the top thereof and the journals of the rolls c⁶¹ with the cams k in the position indicated in Fig. 5, that upon 55 turning the said cams by means of the handle k' the cut-off frame will be forced down upon the top of the cotton in the bale and thereafter secured in place by means of the hooks g, as hereinbefore pointed out.

60 When the turn-table B is revolved on its supports to carry the preliminary bale to the finishing side of the press and to place the empty box or chamber from which the completed bale has been removed under the bale-forming mechanism, it will be evident that 65 some little time will be lost in commencing the preliminary bale, due to the fact that the

plunger of the pressure device A³ must be raised into the bale-box to place the usual follower E² in close proximity to the bale-forming surfaces E E', and in order to overcome this objectionable delay I have provided on each bale-box the hooks h, (shown in Fig. 2 and omitted from the other figures to avoid confusion,) the said hooks h being 70 pivoted, preferably, to the side bars g' of the press and having their ends projecting into the recesses h' in the side of the press. The free ends of these hooks h are sufficiently long to adapt them to support the usual follower E² when it is in its uppermost position after the completion of the finishing compression of the bale. These hooks h are so hung to the bars g' that when disengaged from the follower E² by the lifting thereof due to the 75 rising plunger of the pressure device A³ they will swing outwardly sufficiently far to permit the descent of the follower thereafter without being engaged by the ends of the hooks. From this construction it will be evident that after the finished bale is removed from the finishing side of the press the follower E² may engage with the hooks h by 80 manually turning those hooks, with their free ends projecting well into the bale-box, and that 85 thereafter during the rotation of the turn-table and the laying of the few first layers of cotton upon the follower the hooks h will support and hold the follower in its position as 90 shown in Fig. 2; but when the plunger of the pressure device A³ rises beneath the follower and lifts the same toward the bale-forming surfaces or belts E E' the hooks h will automatically swing outward as they are relieved 95 from the weight of the follower, and thereafter as the follower is lowered under the increasing number of laps laid thereon the hooks h will remain in a position not to engage the follower as it descends.

While I have shown the above construction 100 as the form preferred by me, it is evident that the various details thereof may be varied in wide limits without departing from the spirit of my invention—as, for instance, under some conditions the cut-off depressor, hereinbefore 105 described in its various forms as mounted over the bale-forming surface E', might be omitted, and eccentrically-operative hooks g, for instance, might be sufficient to depress the cut-off sufficiently far toward the top of 110 the bale-box to hold the cotton in the desired position away from the bale-forming surface E', so that the bale might be removed from under the said surface—and while I have 115 shown one of the bale-forming surfaces as a 120 continuous belt E it is of course evident that both of said bale-forming surfaces or belts might be formed of a series of sections or endless belts, as g⁵, (shown in Fig. 3,) and that a cut-off depressor might be used on each 125 side of the reciprocating carriage.

The operation of my device may be briefly outlined as follows: The parts being in position as shown in Fig. 2, the carriage C is re-

ciprocated back and forth by suitable mechanism over the top of the bale-box A', laying layer upon layer of the lap of cotton which has been previously deposited in the hopper C' in a light fluffy mass and then formed into a lap and given a drawing action to lay the fibers substantially parallel and produce uniformity in the character of the lap. On each change of reciprocation of the carriage the fingers e' engage the lap as it passes between the bale-forming surfaces or belts E E' and causes the said lap to be folded in an even turn or fold upon the previous layers, the pressure device A³ in the meantime causing any desired upward pressure against the layers of cotton as they are thus laid, and such pressure being maintained equally throughout the formation of the bale by means of the differential balancing device hereinbefore described. When the preliminary bale has thus been laid up layer upon layer and completed, it is necessary to transfer the said preliminary bale to the finishing side of the press without relieving the bale from its baling pressure, and to this end the cut-off F is inserted between the rollers c⁶ and the top of the bale and then forced against the upper layer of cotton by means of the cut-off depressor, so that said cut-off may be engaged by the eccentrically-mounted hooks g on each side of the bale-box. The pressure or upward tendency of the cotton being thus relieved from the bale-forming surfaces E E' and being held in such position by the cut-off, it is readily seen that the turn-table may be moved to transfer the bale to the finishing side of the press, or, if desired, the preliminary bale thus formed may be removed from the press and at a subsequent time subjected to the finishing compression.

By the terms "bale-forming mechanism" or "preliminary-bale-forming mechanism" I mean any form of mechanism that will be operative in the formation of what I here term the "square bale," and by the term "cut-off" as used in the specification and claims I mean any character of device which is adapted to be placed over the top of the bale to hold the cotton in position as the bale is moved from under the bale-forming mechanism.

Having thus described my invention, what I claim, and desire to secure by Letters Patent, is—

1. In a cotton - press, the combination of 55 bale-forming mechanism, devices for acting upon the top layers of cotton to depress the same after the formation of the bale, and means for holding the top layers of cotton in such depressed position as the bale is transferred from the bale-forming mechanism.

2. In a cotton-press, the combination of a preliminary-bale-forming mechanism,a finishing mechanism, devices for acting upon the top of the bale to depress the same after the formation of the latter, and means for holding the top of the bale in such depressed position as the bale is transferred from the pre-

liminary-bale-forming mechanism to the finishing mechanism.

3. In a cotton-press, the combination of a 70 bale-forming mechanism, means adapted to be inserted between the bale-forming mechanism and top of the bale after the formation of the latter for holding the cotton in position in the bale, and a depressor for forcing said 75 means upon the top of the bale prior to removal from the press.

4. In a cotton-press, the combination of a bale-forming mechanism, means adapted to be inserted between the bale-forming mech- 80 anism and top of the bale after the formation of the latter for holding the cotton in position in the bale, a depressor for forcing said means upon the top of the bale prior to removal from the press, and devices for holding said means 85 in depressed position as the bale is moved from the baling mechanism.

5. In a cotton-press, the combination of a preliminary-bale-forming mechanism,a finish- 90 ing mechanism, and means adapted for inser- 90 tion between the preliminary-bale-forming mechanism and the top of the bale after the formation of the latter for holding the layers of cotton in position as the bale is transferred 95 from under the preliminary -bale - forming mechanism, and devices for depressing said means upon the top layers of cotton prior to the removal of the bale from the press.

6. In a cotton-press, the combination of a bale-forming mechanism for laying cotton 100 layer upon layer in the formation of a bale and maintaining the same under compression during the formation thereof, devices opera- 105 tive upon the top of the bale to depress the same after the formation of the bale, and means for holding the top of the bale in such depressed position as the bale is transferred from the bale-forming mechanism.

7. In a cotton-press, the combination of a traveling carriage, two series of rollers mounted thereon to travel therewith, an endless belt or apron passing around each series of rollers to form a hopper or receptacle for cotton and feed the same between them, a set of rollers mounted on said carriage below the 110 said belts or aprons and a second set of rollers mounted below said first-mentioned set, and means for driving the second set of rollers at an increased speed to draw out the fibers 115 of the lap.

8. In a cotton-press, the combination with a preliminary-bale-forming mechanism, a finishing mechanism, means adapted to be inserted between the preliminary-bale-forming mechanism and top of the bale after the formation of the latter for holding the cotton in proper position in the bale as the latter is transferred from the preliminary-bale-forming to the finishing mechanism, and devices for forcing said means against the top of the 125 bale after the said means have been inserted as specified.

9. In a cotton-press, the combination with a preliminary-bale-forming mechanism; a fin-

ishing mechanism, means adapted to be inserted between the preliminary-bale-forming mechanism and top of the bale after the formation of the latter for holding the cotton in proper position in the bale as the latter is transferred from the preliminary-bale-forming to the finishing mechanism, and devices for forcing said means against the top of the bale after the said means have been inserted as specified, and instrumentalities for maintaining the said means in position on the bale as it is transferred from one mechanism to the other.

10. In a cotton-press, the combination of a baling box or chamber, a hopper, means for reciprocating one of said parts with respect to the other to lay layers of cotton upon each other in the formation of a bale, a pressure device to maintain pressure upon the cotton as it is laid layer upon layer, devices for acting upon the top layers of cotton to depress the same after the formation of the bale, and means for holding the top layers of cotton in such depressed position as the bale is removed from the press.

11. In a cotton-press, the combination of a baling box or chamber and a lap-forming mechanism, means to move one of said parts with respect to the other to lay the lap layer upon layer in the formation of a bale, pressure devices for exerting pressure upon the bale as it is formed, belts for opposing the pressure devices, a cut-off adapted to be inserted over the top of the bale after the formation thereof and means passing through suitable passages in one of said belts for forcing the cut-off upon the top of the bale.

12. In a cotton-press, a preliminary-bale-forming mechanism comprising two series of rollers to feed a lap of cotton layer upon layer in the formation of a bale, a pressure device for maintaining the layers of cotton pressed against said belts as the bale is being formed, in combination with a cut-off adapted to be inserted over the top of the bale after the formation thereof, means passing through suitable passages in one of said belts for forcing the cut-off upon the top of the bale and devices for maintaining the cut-off in position on the bale as the latter is removed from the press.

13. In a cotton-press, the combination of a hopper, a series of rollers at each side thereof, a plurality of belts carried by one of said series of rollers with a space between them, a cut-off, and a cut-off depressor movable in the space between the belts.

14. In a cotton-press, the combination of a hopper, a series of rollers at each side thereof, a belt carried by one of the said series of rollers, a plurality of belts carried by the other series of rollers with a space between them, a cut-off adapted to be inserted between the said plurality of belts, and a cut-off depressor movable in the space between the belts.

15. In a cotton-press, the combination of a hopper, a series of rollers adjacent each side

thereof, a plurality of belts carried by one of said series of rollers with a space between them, and a cut-off depressor comprising handle-bars, and push-bars operable therefrom, said push-bars passing between said belts, and a cut-off adapted to be inserted in the space between the belts and be engaged by the push-bars.

16. In a cotton-press, the combination of a carriage, a hopper mounted thereon and adapted to receive loose cotton direct from a gin or suitable source of supply, series of rollers and bale-forming surfaces mounted on said carriage, means for reciprocating said carriage to lay the cotton layer upon layer in the formation of a bale, the bale-forming surface on one of said series of rollers consisting of several parts spaced apart, a cut-off adapted to be inserted in the spaces between the parts of said bale-forming surface, and a cut-off depressor operable between said parts upon the cut-off.

17. In a cotton-press, the combination of a hopper, a series of rollers adjacent each side thereof carrying bale-forming surfaces, the bale-forming surface on one of said series of rollers comprising a plurality of separated parts, a cut-off depressor operable between the said parts of the bale-forming surface, a cut-off adapted to be inserted in the space between said parts and to be engaged by the cut-off depressor, and retaining devices for holding the cut-off in place upon the top of the bale.

18. In a cotton-press, the combination of a hopper, a series of rollers adjacent each side thereof carrying bale-forming surfaces, the bale-forming surface on one of said series of rollers comprising a plurality of separated parts, a cut-off depressor operable between the said parts of the bale-forming surface, a cut-off adapted to be inserted in the space between said parts and having upturned ends and adapted to be engaged by the cut-off depressor, and retaining devices for holding the cut-off in place upon the top of the bale.

19. A cut-off for holding the cotton in a cotton-bale as the latter is removed from the bale-forming mechanism, said cut-off comprising a series of parallel bars adapted to be placed above the bale after the formation of the latter, said parallel bars being free at one end, and a cross-piece connecting said parallel bars at the opposite end.

20. A cut-off for holding the cotton in a cotton-bale comprising a series of parallel bars, a cross-piece for connecting the bars at one end thereof, said bars being free at their opposite ends, in combination with a bale box or chamber and means carried by said box or chamber for engagement with said cut-off.

21. A cut-off for holding the cotton in a cotton-bale comprising a series of parallel bars, a cross-piece for connecting the bars at one end thereof, in combination with a bale box or chamber, hooks carried by said box or chamber for engagement with the cut-off,

and means for forcing said hooks and the engaged cut-off toward the top of the bale box or chamber.

22. In a cotton-press, a bale-forming mechanism comprising a bale-box and means for laying the cotton layer upon layer in said box to form a square bale, and pressure devices maintaining the layers of cotton under compression as the bale is being formed, said devices comprising a plunger movable within the bale-box in combination with a differential balancing device having gearing connection with said plunger for maintaining the pressure exerted by the plunger on the layers of cotton in the bale-box uniform and equal throughout the formation of the bale.

23. In a cotton-press, the combination of a preliminary-bale-forming mechanism comprising devices for supporting the bale as it is formed, bale-forming surfaces, means for moving one of said parts with relation to the other to lay the cotton in layers and starting-fingers secured to the bale-forming surface to start the lap in the backward fold at the commencement of each movement.

24. In a cotton-press, a bale box or chamber, a traveling carriage, a hopper, a series of rollers and belts mounted on said carriage,

means for moving the carriage back and forth over the bale box or chamber, and starting-fingers secured to the said belts.

25. In a cotton-press, the combination of bale-forming mechanism, means for maintaining the bale under desired compression as the cotton is laid layer upon layer, a follower, and automatically-engaging hooks for holding the follower in position during the laying of some of the preliminary layers and for them to automatically release said follower as the compression means act to compress the layers of cotton.

26. In a cotton-press, the combination of bale-forming mechanism comprising means for laying the cotton layer upon layer, a pressure device for maintaining pressure on the bale as it is formed, a follower and automatically-disengaging hooks for holding the follower in position during the formation of the first part of the bale and for automatically releasing the follower as the pressure device operates to apply pressure to the bale.
